UNITED STATES PATENT OFFICE.

CHRISTIAN O. BARION, OF SAN FRANCISCO, CALIFORNIA.

AUTOMATIC WATER-FEED APPARATUS FOR BOILERS.

Application filed July 28, 1925. Serial No. 46,525.

The present invention relates to an inexpensive and reliable means for automatically feeding water to and accurately maintaining the desired water level in boilers, particularly boilers having condensation return equipment, it being possible to cheaply and easily adapt the invention to boilers of this type without use of force feed apparatus other than that included in the said condensation return equipment.

The invention further resides in the provision of a simply constructed small compact, sturdy and reliable automatic valve which is thermostatically operated and controlled by variations in the water level of the boiler, said valve being subject to a wide range of precise adjustments and capable of long and accurate service at a nominal upkeep cost.

With the above mentioned and other objects in view, the invention consists in the novel construction and combination of parts hereinafter described, illustrated in the accompanying drawing, and set forth in the claim hereto appended, it being understood that various changes in the form, proportion, size and minor details of construction within the scope of the claim may be resorted to without departing from the spirit or sacrificing any of the advantages of the invention.

Referring to the drawing:—

Fig. 1 represents a side elevation of boiler equipment constructed and arranged in accordance with the invention.

Fig. 2 represents a longitudinal sectional view of the automatic valve of the invention.

Fig. 3 is a longitudinal sectional view of a modified form of the valve shown in Fig. 2.

Fig. 4 is a cross sectional view taken on the plane of line 4—4 of Fig. 2.

Referring to the embodiment of the invention shown in detail in the accompanying drawings, the apparatus of the invention which will be later described is incorporated with the boiler 1, equipped with a standard form of condensation return device generally designated 2, this equipment being somewhat modified, however, to provide for the adaptation of my invention thereto. The device 2 for returning condensation to the boiler is of a well known type and includes a receiver 3 receiving condensation from the return pipe 4 and which discharges through a pipe 5 into a trap 6. The condensation may however be

received directly into the trap 6, as a holder therefor if desired. From the trap the condensation is returned to the boiler through a pipe 7. Steam is delivered to the trap by a pipe 7' leading from the boiler to the valve mechanism 8 of the trap. As is well known in the art, water from the receiver passes into the trap 6 which when a predetermined amount of water is contained therein operates automatically through the valve mechanism 8 to admit steam from the pipe 7 into the trap. The pressure of the steam builds up in the trap equal to the boiler pressure and the water in the trap gravitates through the pipe 7 into the boiler. A more detailed account of the operation of boiler of this type is not thought necessary inasmuch as such boilers are well known in the art.

In carrying out my invention with a boiler such as above described, I provide a pipe line 9 leading from a source of water supply 10 to the receiver 3 and by means of an automatic valve 11, automatically supply water to the boiler through the condensation return equipment and therefore eliminate the necessity of using a pump or any force feed device other than that of the condensation return apparatus. An overflow pipe 12 leads from the receiver into the source of water supply 10 and a steam vent pipe 13 from the trap 6 discharges into said source 10 below the level of the supply.

The automatic valve 11 is thermostatically operated but controlled by variations in the water level of the boiler. This valve contains a thermostat and is mounted so that the thermostat is in the plane of the desired water level of boiler. Water and steam from the boiler are conveyed to the valve to operate the thermostat and the thermostat operates to open the valve when the level of the water in the boiler and in the valve is lowered. When the valve is opened, water is fed to the receiver and from thence to the boiler through the condensation return equipment. The hot steam is the operating medium for the thermostat and this medium is held in check by the water from the boiler seeking its level in the valve and partially submerging the thermostat.

The valve 11 is supplied with water from the boiler by a pipe 14, having a connection also with the return pipe 15 of the sight gauge 16. Steam is admitted to the valve 11

through a pipe 17 leading from the upper side of the boiler. The equipment is provided with valved drains 18, 19, 20 and 21 the purposes of which are obvious.

5 By means of the device of my invention an automatic and accurate maintaining of a desired water level may be had very economically.

10 The automatic valve comprises a tubular casing 25 having steam and water intakes 26 and 27 on its upper and lower sides to which the pipes 17 and 14 are connected. Mounted in the casing 25 is a suitable liquid containing thermostat comprising a tube 28 containing an expandible and contractable member 29, fastened at one end as at 29' to the tube 28. One end of the tube 28 is screw threaded as at 30 and is turned through an opening 31 in the end of the casing 25 where it is adjustably held by a flanged adjusting cap 32. The thermostat tube is of considerably less diameter than the casing and is spaced circumferentially therefrom leaving a large chamber for the steam and water 15 which operates the thermostat. The element 29 operates or moves independent of the tube 28 and carries an operating rod 34 which slidably extends through the closed end 35 of the tube and is loosely received in a coupling sleeve 36. A similar rod 37 is similarly received in the other end of the coupling sleeve and extends through a stuffing box 38 at one end of a bore 39 in an extension member 40 of a valve casing 41.

20 This extension is detachably connected to one end of the thermostat casing by means of fastenings 42. The valve casing 41 has nipples 43 and 44 to connect the valve proper in the pipe line to be controlled. A double valve 45 is connected with the rod 37 and has a piston like head 46, having a working fit in a short cylinder 47 attached at one end of the valve casing. A helical expansion spring 48 contained in the cylinder 47 engages the head 46 and holds the valve closed. The tension of this spring may be changed by an adjusting screw 49, operating as shown in Fig. 2 in connection with a screw 50 which bears against the adjacent end of the spring.

25 The two seats 51, and 52 for the portions 53 and 54 of the valve are associated with the two valve passages 55 and 56 controlled by the valve. The portion 53 of the valve receives the water pressure in the supply line so as to hold the valve closed, thus partly relieving the spring of its duty in holding the differential valve against its seats. This balances the valve and insures its working order in lengthening the life of the spring and further in making the operation of the valve easier and smoother.

30 The coupling sleeve facilitates the assembling and disassembling of the valve.

35 The valve is mounted so that the medial

longitudinal line of the thermostat casing is in the same plane as the desired water level of the boiler and the water from the boiler passes through the pipe 14 and seeks its level in said casing, thereby partly submerging the thermostat tube 28. Steam enters the upper half of the casing 25 but approximately one half of the thermostat tube is exposed to steam, that is, when the water in the boiler is at the proper and desired level 40 to be maintained.

When the level of the water in the boiler drops below the predetermined point, the level of the water in the thermostat casing 25 is likewise lowered and more area of the thermostat is exposed to the steam. The thermostat may be arranged and adjusted to provide for an accurate operation thereof slowly or quickly on variation of the level in the boiler and casing 25. When the member 29 of the thermostat expands the rod 34 is pushed and through the coupling 36 pushes the rod 37 so as to unseat the valve 45. Water then flows through the pipe 9 into the receiver 3 and from thence into the trap 6. The trap functions as hereinbefore described when sufficient water is contained therein to tilt the trap and open the valve device 8, to admit steam into the trap until the pressures in the trap and boiler are the same, at which time water will gravitate through the pipe 7 into the boiler.

45 When the level of the water in the boiler rises to the predetermined point, the level in the casing 25 also rises and submerges the thermostat tube so sufficiently to cause it to contract and permit the spring 48 to move the valve against its seats, thus shutting off the feed of water to the receiver 3.

50 The valve may be used with various types of boilers as well as with the present type although it is particularly adapted for use with the present type.

55 The modified valve shown in Fig. 3 is the same as the valve shown in Fig. 2 except as to the adjusting features and its parts, which save for the last named features are designated by the same reference characters used in Fig. 2. In this form the casing 28 is screwed into a cap-like member 55 which is in turn screwed into the threaded outer end 56 of the casing 28. A pin 57 is carried by and extends outwardly from the member 55 through a stuffing box 58 in the outer end of the casing 28.

60 This pin is squared on its outer end so that it may be turned by a wrench or other tool and thereby adjust the member 55 to move the thermostat bodily. The other adjustment brought about by regulating the tension of the spring 48 is effected by means of a cap 59 adjustably screwed on to the valve casing and engaging one end of the spring. The other end of the spring engages a bearing member 60 having a pointed

end bearing on the valve 45. By means of these adjustments the operation of the valve may be precisely regulated over a wide range and made to operate in an accurate and reliable manner. The adjustment of the valve may be easily made without disassembling the valve.

By providing a double seated or differential valve operated by an expansive element which latter is operated by temperature variation, the valve is made more sensitive to variable fluid pressures passing through it and thereby insures a constant water level in the boiler.

My invention may be said to include the provision of a novel and efficacious automatic operating means which although especially adapted for operating valves is more or less of general application. This operating means as will be seen from reference to the foregoing description and accompanying drawings, comprises an expansive element in a casing which latter contains both liquid and gaseous (steam) fluids, the level of the liquid fluid being predetermined and the operation of the said means being brought about by variations of the predetermined level of the liquid fluid. The level of the liquid fluid (boiler water) is predetermined to suit operating conditions and in the present instance this level is at the centre gauge cock of the boiler.

The steam intake 26 for the casing 25 is of considerably less diameter than the opening in the water intake 27. In the present

instance I mount a bushing 26' in the nipple comprising the intake 26 and make a very small opening through the center of the bushing. The purpose of this small opening for the steam is to prevent an unintentional 40 operation of the automatic valve such as would take place in "blowing off the column". In opening the valve outlet 21, to "blow off the column", the water in the casing 25 is also blown and if it were not for 45 the retracted intake opening for the steam, the steam would enter the casing in sufficient amount to cause the valve to open and bring about an increase or raising of the water level of the boiler when such an increase is 50 unnecessary. By making the opening small, sufficient steam does not enter the casing 25 when a "blowing off" operation is carried out, to cause an expansion of the expansive element and a subsequent opening of the 55 valve.

I claim:—

Automatic water feed apparatus for boilers comprising the combination with a boiler, a condensation receiver, and a means 60 in operative association with the boiler and receiver and operating to return condensation to the boiler, of a source of water supply connected with the receiver and a thermostatically operated valve controlled by 65 variations of the water level of boiler which valve controls the flow of water from the source to the receiver.

CHRISTIAN O. BARION.
